UNITED STATES PATENT OFFICE.

CARL A. SPIESS AND JOSEPH C. HEIN, OF MILWAUKEE, WISCONSIN.

FRUIT-JAR.

SPECIFICATION forming part of Letters Patent No. 783,551, dated February 28, 1905.

Application filed December 9, 1903. Serial No. 184,386.

To all whom it may concern:

Be it known that we, CARL A. SPIESS and JOSEPH C. HEIN, residing at Milwaukee, in the county of Milwaukee and State of Wisconsin, have invented a new and useful Improvement 5 in Fruit-Jars, of which the following is a description, reference being had to the accompanying drawings, which are a part of this specification.

Our invention relates to certain new and useful improvements in fruit-jars, and has for its object to provide a closure for a jar or other receptacle by which the cover may be easily and quickly applied and removed and which 15 will be perfectly tight when sealed.

With the above and other incidental objects in view the invention consists of the devices and parts or their equivalents, as hereinafter set forth.

Referring to the accompanying drawings, in which like characters of reference indicate the same parts in the several views, Figure 1 is a vertical section of a jar-closure, illustrating our invention. Fig. 2 is a transverse section thereof, taken on the line 2 2 of Fig. 1; and Fig. 3 is a side elevation showing the open socket connection, the clamping-screw being broken away.

In the drawings, 7 represents a jar or other receptacle of glass, porcelain, or other desirable material, provided with the slightly-contracted neck portion 8, producing the external shoulder 9.

An inverted-cup-shaped cover 10 has its 30 pending peripheral flange 11 resting on a resilient gasket 12, of rubber or suitable material, which is seated on the shoulder 9, the neck 8 of the jar telescoping within said flange 11.

On one side of the jar 7, just beneath the 40 shoulder 9, is an indentation or socket 13, which may be of any suitable shape, but is preferably, as shown, with a horizontal upper wall and an inclined lower wall, the inclined inner wall of the indentation merging with the 45 inner surface of the neck portion 8 of the jar, leaving the solid block of material between the socket and the shoulder 9. On the opposite side of the jar is a similar indentation or socket 14; but one side thereof is open, the indentation varying in depth as determined by a

curved line in the shape of an arc about the socket 13 as a center and ending abruptly in a stop-shoulder 15.

A clamp member 16, preferably of sheet metal and of a U shape, has its ends bent inwardly to form engaging hooks 17, and through a perforation in its enlarged central portion is threaded a clamp-screw 18, having a ring 19 passed through its perforated upper end. 60

The bail-like clamp member 16 is adapted to have one of its hook ends 17 placed in the socket 13, and said member is then swung on said hook end as a pivot, so as to enter the other hook end 17 in the open socket 14. When 65 such swinging motion is limited by the engagement of the hook end 17 with the stop-shoulder 15, the clamp-screw 18 is turned down by means of ring 19 into engagement with the cover 10, and the continued turning of said 70 clamp-screw tightly clamps the cover 10 and shoulder 9 together, and the interposed rubber gasket 12 being compressed between them effectually seals the jar. When it is desired to remove the cover 10, it is only necessary to 75 loosen the screw 18 and swing the clamp member 16 on the hook end 17, which is seated in the pivotal socket 13, so as to remove the other hook end from socket 14, and the cover is again 80 free to be removed.

From the foregoing it will be seen that we have provided a jar-closure by which the cover may be clamped with great pressure without danger of the parts slipping or breaking and which may be quickly and easily applied or 85 removed.

What we claim as our invention is—

1. In a jar-closure, a jar, a cover therefor, a clamp member having hook ends and provided with means for engaging the cover, said 90 jar having a socket in which one end of the clamp member may be pivotally mounted and having another socket into which the other end of the clamp member may be entered and seated by swinging said clamp member pivotally in the first-mentioned socket.

2. In a jar-closure, a jar having a pivotal socket on one side and an open socket on the other side, a cover for the jar, a clamp member having hook ends, one hook end adapted 100

to turn in the pivotal socket and thereby swing the other hook end through the opening of the other socket, and means carried by the clamp member to bear upon the cover.

- 5 3. In a jar-closure, a jar having a pivotal socket on one side and an open socket on the other side in the shape of an arc with the pivotal socket as its center, a cover for the jar, a clamp member having hook ends, one hook 10 end adapted to turn in the pivotal socket and thereby swing the other hook through the opening of the other socket into engagement therewith, and means on the clamp member to bear upon the cover.
- 15 4. In a jar-closure, a jar having a reduced neck forming a shoulder, a cover having a depending flange to be seated on said shoulder, a gasket interposed between the flange and shoulder, said jar being provided with indentations or sockets on its opposite sides just beneath the shoulder, one of said indentations having an open side and being shaped to an arc on the other indentation as a center, said 20 open-sided perforation having its other side forming a stop-shoulder, a clamp member provided with hook ends and adapted to engage one end in one indentation and swing the other end through the open side of the other indentation and against the stop-shoulder thereof, a screw threaded through the clamp member and adapted to bear upon the cover, and a ring carried by the screw.
- 25

swing the other through the open side of the other indentation and engage against the stop- 30 shoulder thereof.

5. In a jar-closure, a jar having a reduced neck forming a shoulder, a cover having a depending flange to be seated on said shoulder, a gasket interposed between the flange and shoulder, said jar being provided with indentations or sockets on its opposite sides just beneath the shoulder, one of said indentations having an open side and being shaped to an arc on the other indentation as a center, said 40 open-sided perforation having its other side forming a stop-shoulder, a clamp member provided with hook ends and adapted to engage one end in one indentation and swing the other end through the open side of the other indentation and against the stop-shoulder thereof, a screw threaded through the clamp member and adapted to bear upon the cover, and a ring carried by the screw.

In testimony whereof we affix our signatures in presence of two witnesses.

CARL A. SPIESS.
JOSEPH C. HEIN.
